UNITED STATES PATENT OFFICE.

ROBERT W. HARDIE, OF ALBANY, NEW YORK.

DESIGN FOR A BRUSH.

SPECIFICATION forming part of Design No. 21,179, dated November 24, 1891.

Application filed October 12, 1891. Serial No. 408,542. Term of patent 14 years.

To all whom it may concern:

Be it known that I, ROBERT W. HARDIE, a citizen of the United States, residing at Albany, in the county of Albany and State of New York, 5 have invented and produced a new and original Design for Brushes; and I do hereby declare the following to be a full, clear, and exact description of the same, reference being had to the accompanying drawings, forming a 10 part thereof.

Figure 1 is a plan view of a brush embodying my design. Fig. 2 is a side perspective of the same.

The brush-head is composed of the bristles 15 A, the band part B, and the cap D. The bristles A project outward from the lower edge of the band part B in a single circular knot, which expands gradually from the band part downward. The band part B is also circular 20 in its general outline, and the upper portion of its inner wall is continuous with the inner wall of the recess b', formed in the extension B' of the band part. The cap D corresponds 25 in its general contour with the inner circular wall of the band part and recessed portion of

the lateral extension B' of said band part. The handle projects laterally from the band part with diverging side portions C and alternate openings c' and transverse rib portions c.

What I claim is—

The design for a brush, as herein described and shown, consisting of a circular band part having its upper inner wall continuous with the inner wall of a recess formed on a lateral extension of the band part, the bristles projecting outward from the lower edge of the band part in a single circular knot expanding gradually from the band part downward, the cap corresponding in its general contour with the inner wall of the band part and extension 30 recess, and the handle extending laterally from the band part with diverging side and alternate open and transverse rib portions. 35

In testimony whereof I affix my signature in presence of two witnesses.

ROBERT W. HARDIE.
